Atty.

UNITED STATES PATENT OFFICE.

SPENCER H. ST. JOHN, OF LONG BEACH, CALIFORNIA.

WELL-PIPE SCREEN.

Application filed December 21, 1921. Serial No. 524,004.

To all whom it may concern:

Be it known that I, SPENCER H. ST. JOHN, a citizen of the United States, residing at Long Beach, in the county of Los Angeles and State of California, have invented certain new and useful Improvements in Well-Pipe Screens; and I do hereby declare the following to be a full, clear, and exact description of the invention, such as will enable others skilled in the art to which it appertains to make and use the same.

This invention relates in the main to oil wells, and the object of the invention is to provide the tubular casing of such wells with screens adapted to exclude sand and other foreign matter, and admit the liquid product.

The invention comprises certain improvements in such screens and in the method of attaching the same to the well-pipe, as will be hereinafter fully set forth and claimed.

In the accompanying drawing, forming a part of this specification, Fig. 1 is a front elevation of my improved screen as applied to a pipe. Fig. 2 is a central, vertical section of the same. Fig. 3 is a central, transverse section of the same. Fig. 4 is a front elevation of a modified form of screen. Fig. 5 is a central, vertical section of the same. Fig. 6 is a central, transverse section of the same. Fig. 7 is a cross section lengthwise of the screen blank as used in Fig. 1, before bending to final form. Fig. 8 is a cross section of the blank screen as used in Fig. 4, before the final bend. Fig. 9 illustrates the type of milling cutter used in forming the screen seat in Fig. 1, and Fig. 10 illustrates the milling of the seat in Fig. 4.

In the drawing, the numeral 5 denotes a fragment of well-casing such as is used for deep wells. At one or more points in the side of this pipe it is necessary to make openings to admit oil, or the like, the end being supposed to be closed. These openings must be effectually protected by suitable screens, or foreign matter will enter and partially or completely clog the well. This has already been done in many ways, but never, to my knowledge, by the use of a perforated single plate fitted to an undercut seat in the pipe.

In preparing the seat for the screen a hole 6 is first bored through the pipe. A concave seat is then milled adjacent to the hole, the

milling being such as to produce an undercut to retain the screen-plate 8 or 8^a, at the sides. 55 The seat shown in Figs. 1, 2 and 3 is best formed by a milling cutter of the type shown in Fig. 9, by first feeding down, and then sidewise, thus forming a T-groove or seat, with retaining side-ribs 9. Into this seat is 60 slipped the screen-plate 8, first punched with narrow slots 8^b, and then bent to the proper curvature. A little inbending of the ends of the ribs at 9^a locks the screen securely in position. 65

The type of screen shown in Figs. 4, 5 and 6 involves the same principle of construction, but differs somewhat in form. By the use of a milling-cutter such as illustrated in Fig. 10 the concave seat is formed 70 with dovetailed sides, and curved as indicated. It is evident that a screen-plate once inserted in such a seat cannot come out or move endwise, if set snugly in place. This may be done by blanking out the screen-plate from stock curved as shown in Fig. 8, 75 setting it in place, and then flattening out the original curvature, thus spreading the plate into the dovetailed seat, and preferably curving it to fit the concave thereof, as shown 80 in Fig. 5, though it would not be impossible to leave the plate perfectly flat, with fairly good results.

In the figures illustrating the modified form of screen and attachment the slots have 85 been shown running lengthwise of the plate and pipe. The crosswise disposition of the slots is preferred, however, because in the seating of the plate its bending spreads the slots on the inner side. This is a very im- 90 portant feature, since it gives inside clear- 95 ance, and any matter, whether oil, or substances that would tend to clog the screen, are easily sucked up by the action of the pump, or the flow of the liquid, if a flowing well.

The invention admits of the use of screen plates which may be very rapidly punched from fairly thick malleable stock (preferably sheet brass), and may be quickly and permanently secured in place without threading, soldering, or other slow operations. 100

Having thus described my invention, I claim:

1. A screen for well-tubing provided with 105 narrow slots, and bent transversely of the

slots for seating in the tubing, the screen being flattened as inserted whereby the slots are spread on the inner side.

2. Combined with well-tubing having concave, laterally undercut seats, outwardly concave screen-plates fitting in said seats and held in place at the undercut sides.

3. Combined with well-tubing having laterally undercut seats formed therein, per-
10 forated screen-plates adapted for attachment

in said seats, being first bent and narrowed for insertion, and finally flattened to spread and fit snugly in the seats.

In testimony whereof I affix my signature in presence of two witnesses.

SPENCER H. ST. JOHN.
